ATTORNEY

UNITED STATES PATENT OFFICE.

ROY S. TROYER, OF AURORA, OHIO.

ROAD-MATERIAL SPREADER AND SURFACER.

Application filed January 30, 1929. Serial No. 336,123.

My invention is an improvement in apparatus for scraping and crowning roadway surfaces.

It is one of the objects of my invention to construct an apparatus for scraping and crowning roadway surfaces which is capable of adjustment for straddling roadways of various widths.

Another object of my invention is to construct an apparatus of the above named character which is sturdy, rigid, and very simple, and which is capable of economical construction of standardized market materials.

15 A further object of my invention resides in effectively bracing a roadway surface scraping and crowning apparatus capable of adjustment to roadways of various widths, and in maintaining the effective, 20 braced condition in any one of the adjusted positions of the apparatus.

Other objects and advantages of my invention will become more apparent as the following description of one embodiment 25 thereof progresses, reference being made to the accompanying drawings, in which like reference characters are employed to designate like parts throughout the same.

In the drawings:
30 Fig. 1 is a top plan view of an embodiment of my invention.

Fig. 2 is a side elevation of the same.

Fig. 3 is a rear elevation thereof.

Fig. 4 is a front elevation of the same.

35 Fig. 5 is an enlarged section taken on a line 5—5 of Fig. 1, and

Fig. 6 is an enlarged section taken on line 6—6, Fig. 1.

In carrying out my invention according 40 to the embodiment illustrated in the drawing, I provide a substantially rectangular frame including the longitudinals or side members 1, which are preferably formed of a standard channel iron or beam section. 45 The longitudinals 1, are superimposed upon the channels 2 and are secured thereto by means of bolts or the like 3. It will be noted that the flat vertical walls of the channels 2 are disposed inwardly of the 50 frame to face one another, providing a means for squaring off the edges of the roadway as the apparatus is moved therewith. The channels 2 also are supported on the filler blocks 4 which engage the roadway surface and support the main frame,

including the longitudinals 1 in a desired position above the surface of the roadway.

The frame also includes lateral members comprising telescopic sections 5 and 6, and 7 and 8, likewise preferably formed of standard channel iron or beam sections. The sections 5 are adjustably supported at their outer ends upon the forward ends of the longitudinals, which are apertured at spaced intervals, as at 9, to receive the pins or bolts 10 passing through the opening in the ends of respective sections 5. The sections 6, adjustably secured to the sections 5 by means of the bolts 11 which may be inserted in any of the registering series of openings 12 formed in the sections 5 and 6, and secured in place by the nuts 13.

The telescopic lateral sections 7 and 8 are also preferably formed of standard channel iron or beam sections, the outer ends of which are rigidly secured to and supported upon the longitudinals 1 near their rearward extremities, as at 14. These lateral telescopic sections 7 and 8 are likewise adjustable laterally of the frame, the said sections 15 being apertured at spaced intervals as at 16, so that the sections may be slid one upon the other to the required adjustment corresponding to the adjustment of the sections 5 and 6. Bolts 17 are then passed through 20 certain of the registering openings 15 and secured in place by the nuts 18.

It will be seen therefore that I have provided a frame for straddling a roadway, which is capable of lateral and longitudinal 25 adjustment to roadways of predetermined width.

I have also provided means for securely diagonally bracing the frame in any of those adjusted positions. This means includes the 30 forwardly converging diagonal channels or beams 19, shown as pivotally connected and supported at their forward ends to the channel 6 by means of a single pin 19, and pivotally connected at their rearward ends to the respective telescopic channel sections 7 by means of the pins 20 and the supporting brackets 21. To the rearward ends of the diagonals are secured suitable bearing plates 22 and 23 having aligned openings 35 therethrough for the passage of the pin 20. The forward ends of the diagonals are provided with bearing plates 24 and 25 having aligned openings for receiving the pin 19.

It will be noted, in referring more par-

ticularly to Fig. 4, that the substantially vertical flat walls of the diagonals 18 are disposed outwardly toward the flat sides of the channels 2. Adjustably secured to the 5 vertical flat walls of the scraper channels 18 are scraper plates 26 having elongated vertical slots 27 formed therein for receiving the projecting ends of the bolts 28 carried by the scraper channels. In this manner the 10 scraper plates may be adjusted vertically on the channels 18 to a scraping level slightly below the material engaging edges of the crowning plates 29. It will be observed that the scraping plates 26 are adjustable independently of one another and of the crowning plates carried by the laterals 7, providing a suitable range of adjustment for all the road surface members. Thus the diagonals not only effectively brace the frame in 15 any of its adjustments, but also constitute forwardly converging scraper members for engagement with the material on the road surface as the frame is moved therealong to force the excess material on the roadway 20 surface outwardly toward the vertical edging faces of the channels 2.

I have provided means for crowning the 25 surface of the roadway which includes vertically adjustable crowning plates 29 adjustably secured to the laterals 7, as shown more clearly in Figs. 3 and 4. These plates are slotted vertically at spaced intervals as at 30, for receiving the projecting ends of supporting pins or bolts 31, which project 35 through openings in the laterals 7. The road surface engaging edge 32 of each of the plates 29 is inclined slightly upwardly toward the longitudinal axis of the frame to produce a corresponding inclined contour 40 or crown to the road surface as the frame is moved therealong.

It will be noted that the crowning plates 45 normally extend slightly below the road surface engaging edges of the scraper plates on the diagonals 18 and are disposed behind these diagonals so that in moving the frame forward along the roadway the excess material is scraped from the roadway toward the longitudinals before the crowning plates 50 engage the scraped surface.

In use the operation of my invention illustrated in the accompanying drawings, may be described as follows:

Assuming that the apparatus is to be set 55 up for scraping, crowning and for leveling a roadway surface of predetermined width, the longitudinals including the beams 1 and 2 and the filler blocks 4 are first set up along the opposite sides of the roadway the flat vertical walls of the beams 2 facing one another. The lateral section 8 is secured in telescopic relation to the laterals 7 and secured thereto in the desired adjusted position by means of the bolts 16. The diagonals 60 18 are pivotally connected at their rear ends

to the laterals 7 and converge forwardly where their forward ends are secured together and suspended from the lateral section 6 by means of the pin 19. In completing the assembly of the apparatus, the laterals 5 are adjusted and secured at their outer ends to the longitudinals 1 and are secured to the lateral section 6 by means of bolts 11 passing through the registering openings. The crowning plates 29 may be 70 secured to the respective laterals 7 and adjusted to the desired elevation with respect to the road surface. In a like manner the scraper plates 26 are secured to the scraper channels 18 at the desired elevation. 75

It will be seen that my invention provides for a very sturdy, yet simple frame and bracing structure, the frame being capable of adjustment to roadways of predetermined width, and being securely braced in any of 80 these adjustments.

It will also be seen that my invention provides for economical construction, since the frame and bracing members may be formed of standardized market materials such as 90 standard channel iron or beam sections.

Various changes in the details of construction may be made without departing from the spirit of my invention or the scope of 95 the appended claims.

I claim:

1. An apparatus of the class described including a substantially rectangular road straddling frame, comprising spaced longitudinal frame members, telescopic sectional 100 lateral members connecting the longitudinals, the telescopic sections thereof being capable of selective adjustment one upon the other whereby the longitudinals may be spaced to straddle a roadway of predetermined width, and substantially diagonally disposed scrapers converging toward the forward end of the frame, said scrapers being pivotally secured to certain of the lateral frame sections to brace the frame in any one 105 of its adjustments.

2. An apparatus of the class described including a substantially rectangular road straddling frame comprising spaced longitudinal frame members, telescopic sectional 115 lateral members connecting the longitudinals, the telescopic sections thereof being capable of selective adjustment one upon the other whereby the longitudinals may be spaced to straddle a roadway of predetermined width, and substantially diagonally disposed scrapers converging toward the forward end of the frame, said scrapers being pivotally secured to certain of the lateral frame sections to brace the frame on anyone 120 of its adjustments, and road surface crowning plates laterally suspended within the said frame.

3. An apparatus of the class described including a substantially rectangular road 130

straddling frame comprising spaced longitudinal frame members, telescopic sectional lateral members connecting the longitudinals, the telescopic sections thereof being capable 5 of selective adjustment one upon the other whereby the longitudinals may be spaced to straddle a roadway of predetermined width, certain of said lateral sections being supported by the longitudinals and capable of 10 adjustment along the same.

4. An apparatus of the class described, including a substantially rectangular straddling frame adjustable laterally for straddling roads of predetermined width, and 15 means for bracing the frame diagonally in any one of its adjusted positions, said bracing means being suspended within the frame and engageable with the material of the roadway to scrape off an excess of such material toward the longitudinal members of 20 the frame.

5. An apparatus of the class described, including a substantially rectangular frame adjustable laterally for straddling roads of 25 predetermined width, means for bracing the frame diagonally in any one of its adjusted positions, and crowning plates carried by the frame and adjustable therewith, said bracing means comprising angularly disposed scrapers 30 pivotally secured at their ends to the frame laterals and engageable with the material of a roadway to strike off an excess of such material.

6. In an apparatus of the class described, 35 a frame comprising channelled longitudinal members, the flat sides thereof being inwardly disposed, lateral members connecting

the longitudinals and comprising channelled telescopic sections capable of selective adjustment one over the other, certain of said 40 lateral sections being capable of adjustment along the longitudinals, and channelled diagonal scraping members pivotally secured to certain of said lateral sections and converging forwardly of the frame, their 45 converging ends being pivotally suspended by one of the lateral sections, whereby excess material on the roadway surface is engaged by the flat sides of the scraper members and fed outwardly toward the adjacent flat faces 50 of the longitudinals, said scraper members forming with the laterals and longitudinals effective bracing means for the frame in any one of its adjusted positions.

7. An apparatus of the class described 55 including a substantially rectangular frame adjustable laterally for straddling roads of predetermined width, means for bracing the frame diagonally in any one of its adjusted positions, and road surface crowning plates 60 carried by the frame and adjustable therewith, said bracing means comprising forwardly converging channel members pivotally connected at their point of convergence to the forward lateral frame members, and 65 vertically adjustable scraper plates carried by the said channel members for engaging and striking off an excess of the material of the roadway as the frame is moved therealong. 70

In testimony whereof, I hereunto affix my signature.

ROY S. TROYER.
